UNITED STATES PATENT OFFICE.

AMOS F. LADWIG, OF WATERLOO, IOWA.

COMBINATION HANGER.

Application filed August 8, 1925. Serial No. 49,027.

My invention pertains to improvements in combination hangers, and the object of my improvement is to supply a device of this class which combines different and associated elements, which elements may be used as bracket hangers or otherwise as desired and of which certain are foldable or removable for convenience when not in use, or to be stored or packaged for carriage.

10 With the above and other objects in view, as will be hereinafter apparent, the invention consists in general of certain novel details of construction and combination of parts hereinafter fully described, illustrated 15 in the accompanying drawings, and specifically claimed, it being understood that changes in the precise embodiment of invention herein disclosed can be made within the scope of what is claimed without departing 20 from the spirit of the invention.

In said drawings, Fig. 1 is a side elevation of the device, showing the main bracket hanger extended, and Fig. 2 is a front elevation thereof, but showing the main bracket 25 hanger swung back parallel with its supporting wall plate.

The device contains a supporting vertically disposed wall plate 1, having its lower diminished end shaped into an upwardly 30 and forwardly bent hook 16. The plate 1 has pressed out medial and apertured bearing lugs 4 and 15, the latter being a pair of spaced forwardly projecting like lugs whose apertures are in alignment vertically with the bearing aperture in the upper bearing lug 4 to receive the rockable vertical shaft part 6 of an integral wire rod 7-2 whose members are substantially parallel in the greater extent of their lengths and also horizontal to 35 project forwardly when extended. This rod is resilient but should be of stiffness sufficient to permit it to bear a suspended weight within its designed limit without deflection.

The lower member 2 has a terminal eye 3 mounted loosely about the lower end part of 45 the shaft member 6. The upper lug 4 has a vertically disposed termination having a medial rectangular notch 5 to receive and hold the abutting part of the bracket member 7 when the member is extended as shown in 50 Fig. 1.

The outer angles of the lug 4 are rounded in order to facilitate the sliding movement 55 thereover of the member 7 in order to swingingly extend it from its retracted position shown in Fig. 2 to its extended position

shown in Fig. 1, for the member 7 yields elastically upwardly when some sufficient pressure is applied to its lower end, thus permitting it to rise and clear the lug corner before being dropped into the notch 5 in extended position, for the eye 3 of the bracket lower member 2 is stopped by the upper one of the lower pair of lugs 15.

The outer ends of the members 7 and 2 are 60 integral with a vertically disposed part 8. The rod may be shaped by bending so as to provide its upper part 7 with upwardly directed looped standards as at 14 where the loop is provided with a half turn twist at 65 its base which renders it stiff, while the outer standard 10 has a similar twist at 9 to likewise impart stiffness and tie its parts together unyieldingly, the upper terminal of the loop being slightly bent forwardly 70 at 11.

An auxiliary hanger bracket 25 of arcuate shape, horizontal and forwardly projecting, is removably supported upon the upper part of the wall plate 1. This bracket 80 is shaped from a somewhat lighter rod than the rod bracket 7-2. It is twisted at points 23 at each side to provide upstanding ears or short looped standards 24 and downwardly directed parts 22, the rod being then 85 bent inwardly slopingly at 21 and again to provide vertical parts, then again being bent to provide shouldered rearwardly directed parts 26, thence being bent downwardly into the pair of terminal stems 20.

Each stem 20 is removably mounted in bearing apertures in vertically aligned lugs 17 and 18 pressed forwardly from the wall plate 1, the upper lug 18 having an upwardly directed and medially notched termination to interlock with the part 26 of the bracket 25.

The main bracket 7-2, in its upper length or reach may have its part 12 aligned with the part 7 if desired.

The terminal hook 16 of the plate 1 may receive loops of garments or other things. The various standards 11, 14 and 24 are used as hangers for concave objects or to engage certain parts of garments or other things whose main portions are supported upon either or both of the brackets 25 and 7-2, whether in certain cases the bracket 7-2 is extended or retracted against a wall or a supporting structure as the inside of a cabinet, closet or other inclosure, or a wall or door.

Neckties or other garments may be draped suspendingly upon the upper bracket 25, thence over or upon the bracket 7-2, and when the latter is retracted against the wall, will hold the lower parts of the suspended articles between the bracket 7-2 and the wall to clear other objects, yet be available for easy and ready removal. The looped standards 14 and 11, as also the standards 10 24 may be used to loop different portions or apertured parts of garments upon whose main bodies are supported without creasing upon one or both of said brackets.

Having described my invention, what I 15 claim as new, and desire to secure by Letters Patent, is:

1. A device of the character described, comprising a vertically disposed and elongated back-plate, said plate having a plurality of pressed-out apertured bearing-lugs, a bracket-hanger consisting of an elastic rod bent to have an end member serve as a rock-shaft and seated loosely in said bearing-lugs, said rod having end-connected substantially 25 parallel reaches and having at its other end a terminal eye mounted loosely upon said shaft part and engaged between two lower bearing-lugs, and engaging means upon the

uppermost bearing-lug engageable by the upper reach of the rod yieldingly to hold the 30 same releasably in either of two positions horizontally relatively to the back-plate.

2. In a device of the character described, a supporting body, vertically spaced bearings with aligned apertures on said supporting body, a rectangular bracket device consisting of an elastic rod bent at different places to provide vertically spaced horizontal bracket parts connected at their outer ends by a vertical strut part, the upper 40 bracket part having an end part depending rockably through the upper bearing and also through the lower bearing, an apertured stop on said supporting body spaced above the lower bearing and also traversed by said 45 end part of the upper bracket part, the lower bracket part having a terminal eye positioned between said stop and the lower bearing and also traversed by said end part of the upper bracket part, and a plurality of 50 upwardly projecting engaging devices upon the upper bearing for the upper bracket part.

In testimony whereof I affix my signature.

AMOS F. LADWIG.
